PRINTING MACHINE

Emil L. Mueller, Rutherford, N. J.

Application September 22, 1931, Serial No. 564,377

27 Claims. (Cl. 101—269)

This invention relates to a printing machine, and particularly to a printing machine intended primarily for use in the quick and convenient printing of relatively few copies from a given electro-type or the like, the electro-type being readily removable so that it may be readily replaced by another from which copies are desired.

An object of the invention therefore is to provide a printing machine which shall be durable and efficient in the printing of copies in this manner.

A further object is to provide a printing machine including means to removably retain an electro-type, a printing roll for rolling over said electro-type, inking means for inking the electro-type, means by which the roll is adapted to carry the paper sheet so that said sheet will be printed as the roll traverses the electro-type in one direction, means to prevent printing contact between the roll and the electro-type when the roll traverses the electro-type in the opposite direction, means by which the paper sheet is accurately fed to and held by the printing roll preparatory to movement of the roll over the electro-type for performing the printing operation, means to insure release of the printed sheet for removal after the printing operation has been completed, manually controllable power means for causing the printing roll to move in opposite directions over the electro-type, and automatically operable means to insure against undesirable movement of the printing roll beyond its intended limits in opposite directions.

A further object is to provide means whereby the printing roll mechanism may be moved manually whenever so desired.

A further object is to provide inking rollers and a carriage therefor and to provide means whereby said carriage may be moved either as a unit with the printing roll mechanism or manually as a separate unit as desired.

A further object is to construct the mechanism so that ample free space may be available for inserting and removing electro-types as desired, also ample access to the ink carrying plate and to so arrange the parts of the mechanism as to insure movement of the inking rollers at least twice over the surface of each new electro-type prior to the printing of the first sheet from said electro-type.

Other objects and aims of the invention, more or less specific than those referred to above, will be in part obvious and in part pointed out in the course of the following description of the elements, combinations, arrangements of parts and

applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a side elevational view of a printing machine constructed in accordance with this invention.

Fig. 2 is a top plan view of the structure seen in Fig. 1 but with the paper sheet feeding mechanism being omitted.

Fig. 3 is a vertical longitudinal sectional view through the machine.

Fig. 4 is a fragmentary top plan view, partly in section, illustrating the automatic control for the electric motor employed.

Fig. 5 is a side elevational view, partly in vertical section, of the left hand end portion of the machine showing the parts as they appear when the printing roll is at this end of the machine.

Fig. 6 is a vertical longitudinal sectional view through the portion of the machine seen in Fig. 5.

Fig. 7 is a top plan view of the paper sheet feed mechanism.

Fig. 8 is a fragmentary detail sectional view illustrating the separable connecting means between the printing roll carriage and the inking roll carriage.

Fig. 9 is a fragmentary detail perspective view of a part of the paper sheet feed mechanism employed, and

Fig. 10 is a side elevational view, partly in vertical section, of the right hand end portion of the machine showing the parts as they appear when the printing roll is at this end of the machine.

Referring to the drawings for describing in detail the exemplary structure which is illustrated therein, the reference character **L** indicates a main frame preferably including legs as **1—1** by which the main bed or table portion **2** is elevated at a suitable height from the floor.

The bed **2** is of a general rectangular shape and extending along its opposite longitudinal edge portions are two rack bars **3—3**.

The reference character **G** indicates generally the printing roll mechanism.

The reference character **H** indicates generally the inking roller mechanism.

The reference character **A** indicates generally the paper sheet feeding mechanism.

The paper sheet feeding mechanism is arranged in a stationary position at the left hand end of

the machine, as seen in Fig. 1. It is carried upon a pair of standards 4—4 which rise from the main portion of the machine and which carry at their upper ends a sheet metal table 5 upon which may 5 rest a pile of paper sheets as at 6. The table 5 has an inclined portion 7 along which the sheets may be moved by hand into position, as indicated at 8, where they can be picked off one after the other by the printing roll as will be presently described.

The printing roll mechanism G and the ink roller mechanism H are mounted to travel back and forth along the length of the machine, the printing roll mechanism having carrying rollers 15 as 9—9 at its opposite sides which rest upon tracks 10 which are provided at opposite sides of the main frame for this purpose, and the ink roller mechanism having similar rollers as 11—11 for likewise engaging the tracks 10.

20 The mechanisms G and H are formed separate from each other so that they may be capable of movement back and forth along the machine as independent elements whenever desired, but in order that they may at times traverse the machine as a single element a suitable connecting device is provided, as indicated by the latch 12. This latch 12, see Fig. 8, is shown as being pivotally mounted upon the side frame 13 of the mechanism G and as having a notch adjacent its 25 free end adapted for engaging about a suitable member 14 which is carried by the side frame member 15 of the mechanism H. A rest 16 is provided for holding the latch 12 normally in a position such that when the mechanism G and H are 30 moved toward each other the relatively inclined end surface 17 of the latch will cam against the member 14, the notch of the latch dropping about the member 14 when the two mechanisms have 35 been moved sufficiently together.

40 The member 14 may be a stationary lug provided upon the frame 15 if desired, but preferably it takes the form of an adjustable clamp screw of such character that, as seen in Fig. 8, when the latch is in connecting position the screw may 45 be clamped down tight so as to prevent unintentional disconnection of the latch.

This connecting mechanism may be duplicated at opposite sides of the machine if desired.

50 The printing roll mechanism G includes the opposite side frame members 13—13 and these may be held together in any appropriate manner, as for instance by the tie rods 18—18. Upon one of these side frames is mounted a suitable electric motor as 19 and upon the other is carried a control switch mechanism 20.

55 From the pulley 21 of the motor a sprocket chain 22 extends about a pulley 23 which is carried upon a short shaft 24. The shaft 24 has a pinion 25 thereon in mesh with a gear 26. The gear 26 is mounted loosely upon a shaft 27 and has driving connection with said shaft through the medium of a slippage clutch mechanism 28 so that operation of the motor will drive the shaft 60 27 except in the event of a possible positive stoppage of said shaft 27 as will be presently referred to.

65 The shaft 27 extends entirely across the machine, being mounted in the opposite side frames 70 13—13, and fixed to this shaft spaced apart thereon are two gear wheels as 29 and 30 the teeth of which intermesh with the teeth of the rack bars 3—3 respectively so that rotation of the gears 29 and 30 will cause the printing roll mechanism to move bodily along the length of

75 the rack bars from one end of the machine to the other, in either direction, according to the direction of rotation of the motor pulley 21.

The switch mechanism 20 is shown as being constructed to provide three separate push buttons as 31, 32 and 33, and the wiring, not illustrated, by which this switch mechanism is connected with the motor is such that operation of the button 31 will produce rotation of the motor pulley in a direction to move the printing roll 10 mechanism toward the paper feed A, while operation of the button 32 will produce opposite rotation of the motor pulley to thereby cause the printing roll mechanism to move toward the right hand end of the machine.

15 The button 33 is connected so that whenever it is operated, as in an emergency, the circuit will be broken and the rotation of the motor pulley will be immediately stopped regardless of the 20 position of the printing roll mechanism with respect to the length of the machine.

The reference numerals 34 and 35 indicate two 25 switch mechanisms which are mounted spaced apart adjacent opposite ends of the machine, see Figs. 1 and 4. Carried upon the printing roll mechanism G so as to travel back and forth with the printing roll mechanism are two switch control rods, as 36 and 37, for said switches 34 and 35 respectively. The two switches and their control rods are so arranged that when the printing roll mechanism approaches its left hand extremity, Fig. 1, the rod 36 will engage against the switch lever 38 of the switch 34 and swing said lever to operate said switch, and so that when the printing roll mechanism approaches its 30 right hand extremity the rod 37 will engage against the switch lever 39 of the switch 35 and swing said lever 39 to operate said switch 35.

35 The switches 34 and 35 are connected in the 40 circuit of the motor 19 and are preferably of a character such that when operated they will simply break said circuit and leave the motor idle so that the entire mechanism will stand motionless until the operator again presses one or the other 45 of the buttons 31 or 32.

45 But, if desired, these switches 34 and 35 may be of a character such that when operated they will simply produce a reversal of direction of the motor pulley so that the printing roll mechanism will at 50 once begin its reverse travel along the machine without awaiting pressing of the buttons 31 or 32 by the operator.

The switch control rods 36 and 37 are preferably 55 so mounted upon the side frame of the printing roll mechanism as to be adjustable particularly in a direction longitudinally of the machine, as most clearly indicated in Fig. 4, as in this way the precise moment at which the switches 34 and 35 will be thrown, with respect to the position of the printing roll mechanism longitudinally of the machine, can be determined to a nicety, and this is of importance particularly when the printing roll mechanism is at the left hand end of its travel because at this time the printing roll mechanism 60 is required to co-operate in a most precise manner with the paper delivery mechanism.

65 Suitable stops, as 40 and 41, may be provided at 70 opposite ends of the machine, engageable by fixed parts of the printing roll mechanism, as for instance the tie rods 18—18, as seen in Fig. 3, for positively preventing movement of the printing roll mechanism beyond said stops 40 and 41 at any time. If for any reason the printing roll mechanism should strike against the abutments 75

40 or 41, or if for any other reason, such as over pressure of the printing roll against the electro-type etc., the travel of the printing roll mechanism should be arrested while the motor is still turning, 5 then the slippage clutch 28 will come into use by allowing a certain continued rotation of the motor without requiring movement of the gears 29 and 30, and thus save the machine from being injured.

At some times it is desirable to move the printing roll mechanism by hand, instead of by means of the motor, and to this end the drawings herewith show a hand wheel as 42 mounted upon a shaft 43, said shaft being supported in the side frames 13 of the printing roll mechanism. Upon 10 the shaft 43 is fixed a gear 44 the teeth of which stand in constant mesh with the teeth of a gear 45 which is fixedly mounted upon the shaft 27. Thus, manual rotation of the wheel 42, acting through the gears 44 and 45, will produce rotation 15 of the shaft 27 to move the printing roll mechanism in either direction along the length of the machine at the will of the operator.

The opposite side frame members 15—15 of the ink roller mechanism H may be held together in 20 any appropriate manner, as for instance by the tie rods 46—46. Any appropriate number of inking rollers as 47—47 extend between the side frames 15—15 each rotatably mounted upon said frames. These rollers carry gears as 48—48 25 thereon the teeth of which stand in constant mesh with the teeth of one of the rack bars 3 so that the rollers 47 are positively rotated in their bearings at all times when the mechanism is moving lengthwise along the rack bars. A shaft 49 also 30 extends between the side frames 15 and is pivotally mounted therein. This shaft carries two gears as 50 and 51 fixed thereto and meshing with the teeth of the rack bars 3—3 respectively so as to insure a properly accurate travel of the ink 35 roller mechanism along the rack bars at all times.

40 The shaft 49, at one end, also carries a gear 52 the teeth of which are in constant mesh with a gear 53 mounted upon a stub shaft on one of the side frames 15, and the gear 53 is provided with a 45 detachable handle 54 by which, when the handle is attached, the shaft 49 may be rotated manually to move the ink roller mechanism along the length of the machine at the will of the operator.

The reference character 55 indicates an ink 50 plate which is positioned flat upon the upper surface of the bed plate 2 adjacent to the right hand end of the machine adapted for supplying ink to the rollers 47—47 as said rollers move onto and off of said plate, in the usual manner.

55 It will be here noted that whenever it is desired, as for instance when a fresh supply of ink has just been put onto the ink plate, the ink roller mechanism may be rolled back and forth any 60 number of times over the plate 55, by means of the handle 54, in order to properly distribute the ink with respect to the plate and the rollers 47. At such times the connecting link or links 12 by 65 which the ink roller mechanism is connected with the printing roll mechanism may be disconnected and the printing roll mechanism moved conveniently away to, or near to, the opposite or left hand end of the machine, thereby leaving an open space for the free and unobstructed movement of the ink roller mechanism along the machine not 70 only onto and off of the ink plate 55 but also onto and off of the printing type 56.

The printing-type 56 may be in any desired 75 form but is preferably, as illustrated, in the form of an electro-type mounted upon a supporting bed 57 and held between opposing abutments 58 and

59 after the manner as illustrated and claimed in my pending application Patent No. 1,865,478, July 5, 1932, Quick-change electro holders for printing machines. The abutment 58 is a relatively stationary abutment while the abutment 59 is a relatively movable abutment being carried upon a rod 60 which extends longitudinally of the machine and which is slidably mounted and urged toward clamping position against the electro-type by suitable means such as the coil spring 61. A 10 suitable foot lever mechanism as 62^a is connected, as by means of a bell-crank 61^b with the outer end of the rod 60 for moving said rod out of clamping engagement with the electro-type whenever it is desired to remove said electro-type for the substitution of a different electro-type. In some instances there may be employed only a single one of the clamp members 59, but in the instance illustrated a plurality of said clamp members are shown arranged side by side across the machine mounted 15 upon independently spring pressed slide rods all of said rods being in turn connected with the single foot lever mechanism 62^a as will be readily understood. Where a number of clamp members 59 are employed, as illustrated, only one, or all, 20 of said clamp members may be employed to hold a given electro-type, according to the size of said electro-type.

The elements, forming part of the paper sheet feeding mechanism A, include two or more movable and adjustable stops 62—62 spaced apart adjacent the lower edge of the inclined portion 7 of the table 5 in such position that they will be engaged by the lower edge of the paper sheet 35 where said edge extends beyond the lower edge 35 of the table. These stops have inclined surface portions 63 thereon for guiding the paper sheet relatively downwardly to a precise position against said stops as the paper sheet is slid down the table portion 7 against said stops. 40

The supports for the stops 62, as illustrated, each include a rod 64 which is slidably mounted within a holder 65 and threaded to be engaged by a threaded collar 66 held within the holder in such relation that rotation of the collar 66 will 45 adjust the rod longitudinally of the holder so as to thereby adjust the stops 62 in a direction toward or away from the lower edge of the table.

Projecting outward from beneath the lower edge of the inclined portion 7 of the table is a pair of 50 light leaf spring fingers 67—67 positioned one beneath each of the stops 62 and being received within notches 68 formed in the lower ends of the stops 62, as clearly indicated in Fig. 9. These light leaf spring fingers constitute rests for supporting the projecting parts of the paper sheet as said sheet is moved against the stops, and they co-operate with the inclined surfaces 63 of said stops to define a precise position for the lower edge of the paper sheet and to thereby properly 55 facilitate the gripping of the sheet by the gripper fingers, as 69, of the printing roll.

The holders 65 of the stops 62 are fixed upon a cross shaft 70, see Fig. 7, which is mounted to rock in suitable bearings as 71—71 at opposite 65 sides of the table. An arm 72 is fixed to the cross shaft 70 at one end of said shaft and carries an anti-friction roller 73 which stands in position to be engaged by a cam 74 carried upon the top edge of the adjacent side frame member 13 of the 70 printing roll mechanism when said printing roll mechanism moves toward its left hand position, the cam 74 being shaped to cause the roller to be first lifted and then dropped as the printing roll reaches its appointed position for receiving the 75

paper sheet. This movement of the roller 73 rocks the shaft 70 and causes the stops 62, and the spring fingers 67, which are so shaped that they have a tendency to follow the stops 62 upwardly at this time, to be lifted, as the printing roll approaches, and then dropped so that the lower ends of the stops 62 extend slightly into the cavity 75 of the printing roll when the printing roll comes to rest.

- 10 The cross shaft 70 is provided with a second arm as 76 at its end opposite from the arm 72 and this arm 76 has an anti-friction roller 77 thereon arranged to be engaged by a small adjustable cam 78 which is carried on the end surface of the printing roll 79 in such position that it will engage against the roller 77 to lift said roller, and consequently the stops 62, in just the desired amount and at the precise moment so that the stops 62 will clear the edge wall of the cavity 75, and release a paper sheet, as the printing roll begins its return movement away from the left hand end of the machine.

Any suitable means may be employed to hold the stops 62 normally in their lowered position, and to determine this position, but for this purpose the drawing suggests that a tension spring as 80 may be connected between the arm 72 and the table in such manner as to hold the arm normally pressing against a ledge as 81 of the table.

As a simple expedient to prevent likelihood of retrogressive movement of the paper sheets during the time while said sheets are being engaged by the gripper fingers of the printing roll the drawings herewith suggests the use of one or more small bristle brushes as 82—82 carried upon a cross shaft 83 parallel with the shaft 70. The shaft 83 is freely rotatable in bearings 84—84 at opposite sides of the table 5 and the brushes project laterally from the shaft and are suitably weighted so that the bristles of the brushes bear frictionally against the paper sheets as said sheets pass beneath them. The brushes stand in a diagonal position with respect to the sheets so that while they permit unhindered movement of the sheets downwardly along the table they nevertheless serve to oppose any retrogressive or upward movement of the sheets.

The gripper fingers 69 are mounted upon a rock shaft 85 which is arranged within the cavity 75 of the printing roll, the opposite ends of the shaft 85 being rotatably received in bearings provided in the opposite end walls 86—86 of the printing roll. At one end the shaft 85 projects through the end wall 86 and carries a laterally extending arm 87, and engaging this arm is a compression spring 88 serving always to urge the shaft in a contra-clockwise direction and to thereby always urge the gripper fingers toward a gripping position.

A second laterally extending arm as 89 is connected with the shaft 85, the arms 87 and 89 being preferably in the form of a simple bell-crank as illustrated in Fig. 5, and carries an anti-friction roller 90.

Rotatably mounted upon the adjacent side frame 13 of the printing roll mechanism is a short shaft 91 and carried by this shaft is a gear 92 to which is fixed a laterally extending arm 93, said arm 93 being disposed to swing in the path of the roller 90 for moving said roller against the pressure of spring 88 when said arm strikes said roller, as in Fig. 5.

The printing roll 79 has gears as 94 and 95 at its opposite ends respectively standing always

in mesh with the teeth of the adjacent rack bars 3—3 so that the printing roll will be positively rotated as the printing roll mechanism moves from end to end of the machine as heretofore described.

The gear 92 stands in constant mesh with the gear 95 so that the arm 93 swings around continuously during the travel of the printing mechanism, but it is to be particularly noted that the ratio of gears 92 and 95 is such that the arm 93 will come into engagement with the roller 90 of the grippers 69 only at one position of the printing mechanism, namely just as the printing mechanism reaches its left hand end extreme position preparatory to receiving a sheet of paper beneath the gripper finger, as in Fig. 5.

As the printing mechanism reaches the position Fig. 5 the arm 93 lifts the gripper fingers so that said fingers stand raised when the printing mechanism comes to rest. While the printing mechanism stands at rest the operator slides a sheet of paper as 3 down the table portion 7, beneath the brushes 82 until the lower edge of the paper extends beneath the gripper fingers, as illustrated in Fig. 6, the movement of paper being arrested at this point by engagement against the stops 62.

The return movement of the printing mechanism is now begun and the first fraction of this movement swings the arm 93 backwardly away from the roller 90 so that the gripper fingers snap downwardly under power of spring 88 to grip the lower edge of the sheet. At the same moment the cam 78 lifts the stops 62 as heretofore explained, and the printing mechanism continues on its way toward the right hand end of the machine carrying the paper sheet with it in such manner that said sheet will be applied against the electro-type 56 as will be readily understood.

As the printing mechanism approaches the right hand end of the machine, the sheet having been now printed and being ready for removal, the roller 90 rides against the cam strip 96 by which it is made to swing the gripper fingers open, as seen in Fig. 10, the printed sheet, as indicated at 97 in Fig. 10, being then free for removal by the operator, it being noted that although the gripper fingers, in receiving the sheet at the left hand end of the machine, closed on said sheet while standing in a relatively upper position substantially vertically above the pivot axis of the printing roll, yet in releasing the sheet the gripper fingers stand at one side of the printing roll in approximately the same horizontal plane as the pivotal axis of the printing roll, the upper or rear edge of the sheet being thus disposed in a very natural and convenient position for manual removal of the sheet by the operator.

When the printed sheet has been removed by the operator the printing roll mechanism is caused, either manually by use of hand wheel 42, or by means of the motor 19, as heretofore explained, to return again to the left hand end of the machine for receiving another sheet.

It is apparent that in the operation of the machine the printing roll 79 passes twice over the electro-type, or printing bed, 56 for each printed sheet, once toward the left of the machine for receiving the sheet to be printed, and then toward the right to carry the sheet over the electro-type to effect the printing operation.

At this point it will be noted that the arrangement and spacing of the parts of the machine 75

is such that the ink rollers 47 pass over the electro-type, or printing bed, 56, also twice for each sheet printed, once toward the left as the printing roll moves to receive the sheet, and then 5 toward the right preceding the printing roll as the printing roll moves to effect the printing operation.

It is desirable of course that the surface of the printing roll should have no engagement with the 10 surface of the electro-type 56 during movement of the printing mechanism toward the left for receiving the sheet to be printed, and to this end the drawings herewith show the printing roll 79 to be rotatably mounted by its opposite ends upon 15 two separately rotatable carrying members 98 and 99 which are mounted to rotate in bearings 100 and 101 respectively provided to receive them upon the adjacent side frames 13 of the printing roll mechanism. The bearings 100 and 101 are 20 eccentric with respect to the centre of rotation of the printing roll, the arrangement is such that a slight rotary movement of the carrying members 98 and 99 will cause the pivotal axis of the printing roll to move vertically a sufficient distance to place the surface of the printing roll either in a plane to have printing engagement 25 with the electro-type or in an elevated plane above the plane of the electro-type.

As an appropriate means by which to rotate 30 the carriers 98 and 99 at proper times the drawings herewith show the two carriers to be connected together by a cross shaft 102 which is pivotally mounted by its opposite end portions in the opposite side frames of the printing roll 35 mechanism and which has arms 103—103 fixed to its opposite ends, there being links 104—104 extending between said arms and the respective adjacent carrying members in such wise that a 40 rocking movement of the shaft 102 will produce simultaneous rotary movement of the two carrying members.

Projecting downwardly from the shaft 102 is an arm 105 which carries at its lower end an anti-friction roller 106 in a position to engage against 45 a pair of oppositely positioned stops 107 and 108.

The arrangement is such that when the printing mechanism moves toward the right and the arm 105 abuts against the stop 108 the printing roll is lifted and continues to stand lifted until 50 the printing mechanism moves to its left hand extreme and the arm 105 is swung by engagement with the stop 107. As the printing mechanism moves toward the left, therefore, over the electro-type, it makes no contact with said electro-type, but the engagement of the arm with 55 the stop 107 causes the printing roll to move down again so that as the printing mechanism returns to the right hand end of the machine the surface of the printing roll will have proper printing engagement with the surface of the electro-type.

The frictional engagement between the carrying members 98 and 99 and their bearings is sufficiently great that while it permits of forced 60 rotation of the carrying members when the arm 105 strikes one or the other of the stops 107—108, still the carrying members will be held firmly against movement within the bearings at all other times.

70 The cam strip 96 against which the roller 90 rides for opening the gripper fingers when the printing mechanism reaches its right hand extreme position, as hereinabove described, is movably supported, being in the form of an arm or 75 strip hanging from a pivot as 109. It has a

notch 110 in its edge which, in one position of the arm or strip, fits about a stationary cross rod 111. The pivot 109 and the parts 110 and 111 are so related that when the notch is in engagement with the cross rod, as shown in Figs. 5 3, 5 and 6, the curved edge surface as 112 of the strip will stand substantially concentric with the center of rotation of the printing roll and at such distance from said center of rotation as to permit passage of the gripper-finger-operating-arm 10 89 and roller 90 over it without causing any movement of said arm 89. When however the strip has been moved so that the notch no longer fits about the cross rod 111 but a relatively raised portion as 113 engages against said cross 15 rod, then the curved surface 112 stands eccentric to the center of rotation of the printing roll, the lower end portion of the strip curving relatively inwardly so that the curved edge 112 constitutes in effect a cam for engagement by the 20 roller 90 to swing open the gripper fingers, as illustrated in Fig. 10.

Any suitable means may be employed for supporting and moving the cam strip 96, but for this purpose the drawings herewith show the pivot 25 109 to be formed at the free end of a short arm 114 which projects laterally from a rock shaft 115. Fixed to this shaft is a second arm 116 and from the free end of this arm extends a link 117 by which it is connected with the adjacent printing-roll-carrying-member 98—99 so that the pivot 109 will be moved to alter the position of the cam strip 96 from operative to inoperative position and vice versa each time the 30 arm 105 is swung by engagement with one or the other of the stops 107 or 108 as the case may be.

It will be understood of course that the mechanism for operating the gripper fingers may be duplicated at opposite sides of the printing mechanism or not as preferred.

Suitable guide fingers as 118—118 may be provided, mounted upon a cross rod 119 of the printing roll mechanism for guiding and holding the paper sheets as they move around with the printing roll for the printing operation or as they stand at rest after the printing operation has been completed.

Any or all of the rollers 9—9 or 11—11, by which the printing roll mechanism G or the ink- 50 roller mechanism H, are supported upon the tracks 10 may be adjustable to provide for a properly accurate adjustment of these mechanisms with respect to the electro-type and the ink supplying plate, and to this end the drawings herewith show one of said rollers to be mounted upon a supporting pin as 120 which is eccentrically adjustable in its supporting member, namely in this instance the side frame 13 of the mechanism G. The holding nut 121 by 55 which the supporting pin is connected with the side frame 13 being employed to hold the supporting pin in any rotary position to which it may be adjusted as will be readily understood. Obviously any or all of the rollers 9 and 11 may 60 be adjustably mounted in this same manner, although it is usually sufficient to provide adjustment only for a portion of said rollers.

The normal positions of rest for the various elements of the machine are as illustrated in 70 Fig. 3 and in this normal position the mechanisms G and H are both at their right hand extremes spaced away from the paper sheet feeding mechanism A by a considerable gap or open space as at 122 within which stands, open to easy access,

the electro-type 56 or other printing type employed, the relation of the parts being such that the operator may quickly and easily remove the used electro-type and insert a new one, all in uncramped quarters and open to full and easy view particularly from above so that the electro-type may be properly and accurately positioned and correctly and firmly locked against displacement. The extreme right hand position of the mechanisms G and H is not only an advantageous position for the reasons just mentioned but it is a natural position, being that position in which said mechanisms stand at the completion of the printing operation. And, as above pointed out, the subsequent printing of a sheet from a newly inserted electro-type is preceded always by movement of the mechanisms G and H first toward the left for receiving the sheet and then a return to the right for performing the printing operation, by which movements the printing surface of the electro-type is twice traversed by the inking rollers before the printing impression is made.

A suitable handle 123 may be provided for manually shifting the printing roll up and down so that it will or will not have printing engagement with the electro-type as the case may be at any moment irrespective of the position of travel of the printing mechanism G. The drawing Fig. 1 suggests that such a handle may be arranged in a convenient position upon one of the arms 183 so that the cross shaft 102 may be easily rocked by the operator to rotate the carriers 98 and 99 as heretofore explained with reference to the stops 107 and 108.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A printing mechanism comprising, in combination, a table having printing type thereon at one point in the length of said table, a printing roll mounted to travel back and forth along the length of said table from one side of said printing type to the other being normally at one side of said printing type and adapted to traverse the printing type to the opposite side thereof for receiving a sheet to be printed and to again traverse the printing type to the first side for performing the printing operation, a paper sheet feed mechanism arranged at said mentioned opposite side of the printing type adapted to feed to said printing roll a paper sheet to be printed, an inking roller also mounted to travel back and forth along the length of the table from one side of the printing type to the other and to apply ink to said printing type at each traversing of said printing type, and a latch device to connect the inking roller to travel with the printing roll, said latch device including means automatically operable to connect the inking roller for travel with the printing roll, and said latch device being manually operable at will to disconnect said elements.

2. A printing mechanism comprising, in combination, a table having printing type thereon at one point in the length of said table, a printing roll mechanism mounted to travel back and forth along the length of said table from one side

of said printing type to the other being normally at one side of said printing type and adapted to traverse the printing type to the opposite side thereof for receiving into the printing mechanism a sheet to be printed and to again traverse the printing type to the first side for performing the printing operation, a paper sheet feed mechanism arranged at said mentioned opposite side of the printing type adapted to feed into the printing mechanism a sheet to be printed, and an ink roller connected with the printing mechanism to travel therewith adapted, as the printing mechanism moves toward the paper sheet feed mechanism, to traverse the printing type for applying ink thereto, and adapted, as the printing mechanism returns, to again traverse the printing type for applying ink thereto, the connecting means between the ink roller and the printing mechanism consisting of a pivotally mounted latch carried by one of said elements having a cam portion to engage the other element when the elements are moved into proximity with each other thereby swinging said latch for automatically connecting said elements, said latch being readily manually swingable to disconnect said elements.

3. A printing mechanism comprising, in combination, a table having printing type thereon at one point in the length of said table, a printing roll mounted to travel back and forth along the length of said table from one side of said printing type to the other being normally at one side of said printing type and adapted to traverse the printing type to the opposite side thereof for receiving a sheet to be printed and to again traverse the printing type to the first side for performing the printing operation, a paper sheet feed mechanism arranged at said mentioned opposite side of the printing type adapted to feed to said printing roll a paper sheet to be printed, the table having a rack bar extending lengthwise thereof, the printing roll having a gear engaging the rack bar to cause rotation of the printing roll incident to movement of the printing roll along the table, the printing roll also having gripper fingers for gripping the paper sheet from the paper sheet feed mechanism, and there being means engaging the teeth of said mentioned gear and thereby operable by rotation of the printing roll to operate said gripping fingers for gripping the sheet from the feed mechanism.

4. In a printing machine, the combination with a printing roll mechanism mounted to travel back and forth between two positions along a suitable bed, said mechanism including a printing roll having gear teeth engageable with the bed to cause rotation of said roll in opposite directions during the back and forth travel of said mechanism, and said roll also having gripper fingers for gripping a sheet of paper to be printed, and means comprised in said printing roll mechanism operable by engagement with said gear teeth to move the gripper fingers to gripping position, and other means also comprised in said printing roll mechanism operable to move the gripper fingers to releasing position, said two means for operating the gripper fingers being arranged respectively in diametrically opposite directions with respect to the center of rotation of the printing roll.

5. In a printing machine, the combination with a printing roll mounted to travel back and forth between two positions along a suitable bed and having bed engaging means effective to cause rotation of said roll in opposite directions during

the back and forth travel of said roll, and said roll also having gripper fingers for gripping a sheet of paper to be printed, of means operable by said bed engaging means to thereby operate said gripper fingers.

5 6. In a printing machine, the combination with a printing roll mounted to travel back and forth between two positions along a suitable bed and having gear teeth engageable with the bed to cause 10 rotation of the roll in opposite directions during the back and forth travel of the roll, and said roll also having gripper fingers for gripping a sheet of paper to be printed, of means operable by engagement with said gear teeth to operate 15 said gripper fingers.

7. In a printing machine, the combination with a printing roll mounted to travel back and forth between two positions along a suitable bed and having gear teeth engageable with the bed to cause 20 rotation of the roll in opposite directions during the back and forth travel of the roll, and said roll also having gripper fingers for gripping a sheet of paper to be printed, of a gear wheel mounted to move back and forth with said roll having connection with said gripper fingers to 25 operate said gripper fingers and said gear wheel also having constant driving engagement with said gear teeth so as to be driven by said roll to thereby operate said gripper fingers.

30 8. In a printing machine, the combination with a printing roll mounted to travel back and forth between two positions along a suitable bed and having gear teeth engageable with the bed to cause rotation of the roll in opposite directions 35 during the back and forth travel of the roll, and said roll also having gripper fingers for gripping a sheet of paper to be printed, of means mounted to travel back and forth with said roll and having connections with said gear teeth and with 40 said gripper fingers whereby to operate the gripper fingers by power derived from said gear teeth.

9. In a printing machine, comprising a table and a printing roll mounted to travel back and forth between two positions along said table and having gear teeth engageable with the table to cause 45 rotation of the roll in opposite directions during the back and forth travel of the roll, and said roll also having gripper fingers for gripping a sheet of paper to be printed, the combination therewith of a gear wheel mounted to move back and forth with said roll and having intermeshing engagement with said gear teeth so as to be rotated in opposite directions according to the direction of travel of the roll, and a cam connected 50 with said gear wheel to rotate therewith, together with means by which the cam has operative association with said gripper fingers to operate said gripper fingers.

60 10. In a printing machine, comprising a table and a printing roll mounted to travel back and forth between two positions along said table and having gear teeth engageable with the table to cause rotation of the roll in opposite directions 65 during the back and forth travel of the roll, and said roll also having gripper fingers for gripping a sheet of paper to be printed, together with a spring actuated lever connected with said gripper fingers always urging said fingers to gripping 70 position, the combination therewith of a gear wheel mounted to move back and forth with said roll and having intermeshing engagement with said gear teeth so as to be rotated in opposite directions according to the direction of travel of the roll, and a cam connected with said gear 75

wheel to rotate therewith having operative engagement with said lever to move said lever in a direction to move said gripper fingers to a non-gripping position.

11. In a printing machine, comprising a table 5 and a printing roll mechanism mounted to travel back and forth between two positions along said table said printing roll mechanism including a printing roll having gear teeth engageable with the bed in a manner to insure rotation of the roll 10 in opposite directions during the back and forth travel of said mechanism and said roll also having gripper fingers for gripping a sheet of paper to be printed, the combination therewith of a gear wheel rotatably carried as a part of said 15 printing roll mechanism and having intermeshing connection with said gear teeth, and a cam connected with said gear wheel to rotate therewith, together with means by which the cam has operative association with said gripper fingers 20 to operate said gripper fingers.

12. In a printing mechanism, comprising a table having a paper sheet feed mechanism thereon including a movable stop device against which the paper rests, and a printing roll mechanism 25 mounted to travel along the table to and from said feed mechanism including a printing roll having gripper fingers for gripping a sheet from said feed mechanism, the combination therewith of means carried by the printing roll mechanism 30 to move therewith for engaging said stop device to move the stop portion thereof thereby to release a sheet to said gripper fingers.

13. In a printing mechanism, comprising a table having a paper sheet feed mechanism 35 thereon including a movable stop device against which the paper rests, and a printing roll mechanism mounted to travel along the table to and from said feed mechanism including a printing roll having gripper fingers for gripping a sheet 40 from said feed mechanism, the combination therewith of a cam connected with said printing roll to travel and rotate therewith operable to engage said stop device to move the stop portion of said stop device to release a sheet to said 45 gripper fingers.

14. In a printing mechanism, comprising a table having a paper sheet feed mechanism thereon including a movable stop device against which the paper rests, and a printing roll mechanism 50 mounted to travel along the table to and from said feed mechanism including a printing roll having gripper fingers for gripping a sheet from said feed mechanism, the combination therewith of a cam connected with said printing roll mechanism to travel therewith operable to engage said stop device to move the stop device in a manner to admit said printing roll therebeneath and a second cam connected with said printing roll to travel and rotate therewith operable to engage said stop device to move the stop portion of said stop device to release a sheet to said gripper fingers.

15. In a printing mechanism, comprising a table having a paper sheet feed mechanism thereon including a movable stop device against which the paper rests, and a printing roll mechanism mounted to travel along the table to and from said feed mechanism including a printing roll having gripper fingers for gripping a sheet from 70 said feed mechanism, said feed mechanism including a rod pivotally mounted in a position to extend across the sheet and having stop forming portions extending laterally therefrom into sheet stopping position, said rod also having other 75

- laterally extending parts, said printing roll mechanism including a cam part operable to engage one of said last mentioned laterally extending parts of said rod to rotate the rod for lifting said stop portions, and a second cam connected with said printing roll to travel and rotate therewith operable to engage another of said mentioned laterally extending parts of said rod to rotate the rod for further lifting said stop portions.
16. In a printing machine, comprising a printing roll mechanism mounted to travel back and forth between two positions along a suitable bed, and a motor carried by and movable with said printing roll mechanism, the combination therewith of a pair of separate switch devices carried by the bed spaced apart and connected with the motor operable to cause rotation of the motor in opposite directions respectively, means carried by the printing roll mechanism to engage said switch devices for operating said switch devices alternately as the printing roll mechanism approaches its opposite extreme positions, and connections between the motor and the bed operable to cause said printing roll mechanism to move in opposite directions according to the direction of rotation of the motor.
17. In a printing machine, comprising a table and a printing roll mechanism mounted to travel back and forth between two positions along said table said printing roll mechanism including a printing roll having gear teeth engageable with the bed in a manner to insure rotation of the roll in opposite directions during the back and forth travel of said mechanism and said roll also having gripper fingers for gripping a sheet of paper to be printed, the combination therewith of a cam movably mounted adjacent to said printing roll said cam being movable from its inoperative position ineffectual to cause opening movement of said gripper fingers to its operative position effectual to cause opening movement of said gripper fingers, means whereby the printing roll is mounted for movement between impression and non-impression positions, and means carried by said printing roll mechanism arranged to be moved by engagement with spaced stops on said table to move said cam from its inoperative to its operative position and to move said printing roll to its non-impression position incident to movement of the printing roll mechanism into one extreme and to move said cam from its operative to its inoperative position and to move said printing roll to its impression position incident to movement of the printing roll mechanism into the other extreme.
18. In a printing machine, comprising a table and a printing roll mechanism mounted to travel back and forth between two positions along said table said printing roll mechanism including a printing roll having gear teeth engageable with the bed in a manner to insure rotation of the roll in opposite directions during the back and forth travel of said mechanism and said roll also having gripper fingers for gripping a sheet of paper to be printed, together with a spring actuated lever connected with said gripper fingers always urging said fingers to gripping position, the combination therewith of a cam movably mounted adjacent to said lever said cam being movable from its inoperative position ineffective to cause movement of said lever during rotation of said printing roll to its operative position effective to cause movement of said lever during rotation of said printing roll, and means carried by said printing roll mechanism arranged to be moved by engagement with spaced stops on said table to move said cam between its inoperative and operative position incident to movement of the printing roll mechanism into its opposite extremes. 5
19. In a printing mechanism, a travelling printing roll, a gripper finger carried by said roll movable into and out of position for holding a paper sheet connected with the roll, a rack along which the roll travels, a gear connected with the roll 10 and engaging the rack to cause rotation of the roll as a result of the travel of the roll along the rack, and means including a part inter-meshing with the teeth of said gear so as to be driven during rotation of the roll for thereby moving the 15 gripper finger to one of its positions.
20. In a printing mechanism, a travelling printing roll, a gripper finger carried by said roll movable into and out of position for holding a paper sheet connected with the roll, means to cause 20 rotation of the roll as a result of the travel of the roll, means movably mounted separate from the roll but having driving connection with the roll so as to be driven by rotation of the roll for thereby moving the gripper finger to gripping position 25 as the roll leaves one end of its travel, and other means for moving the gripper finger out of gripping position consisting of a part disposed to be engaged by a part movable with the gripper finger as the roll approaches the opposite end of 30 its travel.
21. In a printing machine, the combination with a printing roll mounted to travel back and forth between two positions along a suitable bed and having bed engaging means effective to cause rotation of said roll in opposite directions during the back and forth travel of said roll, and said roll also having gripper fingers for gripping a sheet of paper to be printed, of means operable by said bed engaging means to thereby operate 40 said gripper fingers as the roll leaves one of its positions, and other means also to operate the gripper fingers as the roll approaches its other position. 35
22. In a printing machine, the combination with 45 a printing roll mounted to travel back and forth between two positions along a suitable bed and having bed engaging means effective to cause rotation of said roll in opposite directions during the back and forth travel of said roll, and said roll also having gripper fingers for gripping a sheet of paper to be printed, of means operable by said bed engaging means to thereby operate said gripper fingers as the roll leaves one of its positions, and other means also to operate the gripper fingers as the roll approaches its other position. 50
23. In a printing machine, comprising a table and a printing roll mechanism mounted to travel back and forth along said table including a printing roll having gear teeth engageable with the 65 table in a manner to insure rotation of the roll in opposite directions during the back and forth travel of said mechanism and said roll also having gripper fingers for gripping a sheet of paper to be printed, a paper sheet feed mechanism disposed at one end of the table into precise relationship with which the roll moves for receiving a paper sheet into the gripper fingers of the roll, a reversible electric motor carried by and movable with the printing roll mechanism and having 70 75

connections with the printing roll to drive the printing roll, and stop means to stop travel of the printing roll mechanism with the printing roll in position to receive a paper sheet from said paper sheet feed mechanism, the combination therewith of means comprised in the connections between the motor and the printing roll effective when travel of the printing mechanism has been stopped by said stop means to permit continued 10 rotation of the motor without corresponding rotation of the printing roll.

24. A printing mechanism, comprising a table having a paper sheet feed mechanism thereon including a movable stop device against which the paper sheet rests preparatory to delivery, and a printing roll mechanism mounted to travel along the table to and from said feed mechanism including a printing roll having a gripper finger for gripping a sheet from said feed mechanism, 15 said printing roll mechanism including a part operable to move said stop clear of the printing roll as said roll approaches the feed mechanism, and said printing roll mechanism having separate means operable to move the stop for releasing the paper sheet to the gripper fingers of the printing roll.

25. A printing machine comprising a table, a carriage mounted to travel back and forth along said table, a printing roll rotatably mounted upon the carriage, a sheet gripper finger carried by said roll to turn therewith, a cam carried by the carriage intended for engagement by a part movable with the gripper finger for operating the gripper finger, said cam being movable from an inoperative position ineffective to operate the gripper finger to operative position effective for operating said gripper finger, and means to move said cam between its inoperative and operative 30 positions incident to rotation of said roll.

26. A printing machine comprising a table, a printing roll mounted to roll back and forth between two positions along said table, a sheet gripper finger carried by said printing roll to turn therewith, a cam mounted to move back and forth along the table in company with said printing roll intended for engagement by a part movable with the gripper finger for operating a gripper finger, means whereby said cam is movable from an inoperative position ineffective to operate 10 the gripper finger to operative position effective for operating said gripper finger, oppositely positioned stops carried by the table, and a member mounted to move back and forth along the table in company with said printing roll arranged to 15 be moved by engagement with said table stops to move said cam between its inoperative and operative positions incident to movement of the printing roll back and forth along the table.

27. In a printing machine, the combination 20 with a printing roll mounted to travel back and forth between two positions along a suitable bed and having bed engaging means effective to cause rotation of said roll in opposite directions during the back and forth travel of said roll, roll 25 lifting means operable to lift the roll from impression to non-impression position with respect to the bed, and said roll also having a gripper finger for gripping a sheet of paper to be printed, of means operable by said bed engaging means 30 to operate said gripper finger while the roll travels adjacent to one of its positions, and connections whereby operation of said roll lifting means will cause further operation of the gripper finger as the roll travels to adjacent its other position. 35

EMIL L. MUELLER.
